UNITED STATES PATENT OFFICE.

CHARLES MENZIES COWAN AND JOHN BROWN, OF MUSSELBURGH, SCOTLAND.

APPARATUS FOR TREATMENT OF PAPER-PULP AND OTHER FIBROUS MATERIALS.

1,324,542.

Specification of Letters Patent.

Patented Dec. 9, 1919.

Application filed February 16, 1918. Serial No. 217,694.

To all whom it may concern:

Be it known that we, CHARLES MENZIES COWAN and JOHN BROWN, subjects of the King of the United Kingdom of Great Britain and Ireland, and residing at Musselburgh, Scotland, have invented a certain new and useful Improvement in Apparatus for Treatment of Paper-Pulp and other Fibrous Materials, of which the following is 10 a specification.

This invention relates to improved apparatus for beating or bruising paper pulp and other fibrous materials and has for its objects, *inter alia*, to economize power, to increase the efficiency of operation and to improve the resultant product.

The improved apparatus comprises, in lieu of the usual beating cylinder or drum and coöperating plate, a pair of closely adjacent peripherally fluted or grooved rollers which are rotated at different speeds in opposite directions and between which the material is passed and thereby beaten.

The rollers are preferably adjustable toward and away from each other to meet requirements.

The flutings or grooves are preferably slightly skew to the axes, which latter are horizontal and lie in the same horizontal 30 plane in parallel relationship.

Any suitable means may be provided for imparting oppositely directed rotary movements to the rollers.

In the accompanying drawings Figure 1 is 35 a side elevation and Fig. 2 a plan and Fig. 3 a vertical section of apparatus embodying the invention in conjunction with separating apparatus or brush such as disclosed in the specification of the co-pending application 40 No. 217,693, filed February 16, 1918. Fig. 4 is a detail view showing the fluted formation of the rollers. Fig. 5 shows diagrammatically the improved apparatus as constituting an adjunct to an existing beating engine.

The same reference letters indicate similar parts in the several views.

As shown, the improved apparatus comprises a pair of fluted rollers 1, 2 revoluble at different speeds in opposite directions 50 within a closed vessel 3 having an inlet 4 on top and an outlet 5 at the bottom.

The flutings are slightly skew to the axes of the rollers which lie in the same horizontal plane in parallel relationship.

The rollers 1, 2 are mounted so as to be adjustable toward and from each other to meet requirements, and receive oppositely directed rotary movements at different speeds through the intermediary of gearing.

What we claim is:—

1. Apparatus for beating paper pulp and other fibrous material in the wet state, comprising a pair of closely adjacent peripherally fluted beating rollers the axes of which are in the same horizontal plane, and between which rollers the material is permitted to flow downwardly, the flutings of said rollers being oppositely skewed, and means for rotating said rollers at different speeds in opposite directions.

2. Apparatus for beating paper pulp and other fibrous material in the wet state, comprising a pair of closely adjacent peripherally fluted rollers the axes of which are in the same horizontal plane, and between which rollers the material is permitted to flow downwardly, said rollers adjustable laterally toward and away from one another, the flutings of said rollers being oppositely skewed, and means for rotating said rollers at different speeds in opposite directions.

In testimony whereof we have signed our names to this specification in the presence of two subscribing witnesses.

CHARLES MENZIES COWAN.
JOHN BROWN.

Witnesses:

HENRY MASON,
ANNE WATT.
